(57) **CLAIM**

The ornamental design for a paint tray liner, as shown and described.

DESCRIPTION

FIG. 1 is an isometric view of a paint tray liner showing my new design;

FIG. 2 is a side view thereof, as taken from the left (unseen) side of FIG. 1;

FIG. 3 is a side view thereof, as taken from the right side of FIG. 1 (the side views are mirror images of one another);

FIG. 4 is a front end view thereof;

FIG. 5 is a rear end view thereof;

FIG. 6 is a top view thereof;

FIG. 7 is a bottom view thereof;

FIG. 8 is an isometric view of a second embodiment thereof;

FIG. 9 is a side view thereof, as taken from the left (unseen) side of FIG. 8;

FIG. 10 is a side view thereof, as taken from the right side of FIG. 8 (the side views are mirror images of one another);

FIG. 11 is a front end view thereof;

FIG. 12 is a rear end view thereof;

FIG. 13 is a top view thereof; and,

FIG. 14 is a bottom view thereof.

UNITED STATES PATENT AND TRADEMARK OFFICE
Certificate

Patent No. D. 612,119 S

Patented: March 16, 2010

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Mark W. Bergman, Minnetonka, MN (US); Christopher M. Bergman, Hopkins, MN (US); Matthew V. Leyden, St. Paul, MN (US); Jeffrey B. Waffensmith, North Oaks, MN (US); and Jeffrey T. Given, St. Paul, MN (US).

Signed and Sealed this Second Day of July 2013.
